UNITED STATES PATENT OFFICE

171,419

COMBINED GLASS HOLDER AND OPENER
FOR BOTTLES AND JARS

George Frederick Muzzy, Malden, Mass.

Application August 25, 1953, Serial No. 26,580

Term of patent 3½ years

(Cl. D44—29)

To all whom it may concern:

Be it known that I, George Frederick Muzzy, a citizen of the United States and residing in Malden, in the county of Middlesex, Commonwealth of Massachusetts, have invented a new, original, and ornamental Design for a Combined Glass Holder and Opener for Bottles and Jars, of which the following is a specification, reference being had to the accompanying drawings, forming a part hereof.

Fig. 1 is a top plan view of a combined glass holder and opener for bottles and jars showing my new design;

Fig. 2 is a bottom plan view thereof;

Fig. 3 is a side elevational view thereof;

Fig. 4 is a side elevational view of the side opposite that shown in Fig. 3; and

Fig. 5 is a front elevational view thereof.

I claim:

The ornamental design for a combined glass holder and opener for bottles and jars, as shown.

GEORGE FREDERICK MUZZY.
